UNITED STATES PATENT OFFICE.

CHARLES FINKEL AND IRA COHEN, OF SEATTLE, WASHINGTON.

STREET-SWEEPER.

1,308,004.

Specification of Letters Patent. Patented June 24, 1919.

Application filed September 11, 1916, Serial No. 119,356. Renewed October 15, 1918. Serial No. 258,289.

To all whom it may concern:

Be it known that we, CHARLES FINKEL and IRA COHEN, citizens of the United States, and residents of Seattle, in the county of 5 King and State of Washington, have invented certain new and useful Improvements in Street-Sweepers, of which the following is a full, true, and exact specification.

Our invention relates to improvements in 10 street sweepers and has for its principal object to provide an improved and novel form of street sweeping device which embodies means for conveying and elevating the sweepings into a cart or wagon. Another 15 object of our device is to provide sweeping means and elevating means both of which are operated from the traction wheels of the device. It is usual in rotary brush sweepers to brush the dirt into piles or windrows after 20 which it is shoveled into the cart or wagon. Our device is designed to load the dirt directly into the wagon as it leaves the brush, thereby obviating the necessity of shoveling the dirt into the wagon.

25 In the drawings Figure 1 is a plan view of our device with parts broken away and others omitted. Fig. 2 is a sectional side elevation of same.

Referring more particularly to the drawings, numeral 1 indicates a wagon bed or box which is mounted upon a front truck having wheels 2 and upon a rear axle 3 to which is secured traction wheels 4, drive gears 5 and secured to the inner side of wheels 4 35 and revolved therewith. Brush hangers 6 are revolvably mounted upon shafts 3, adjacent the gears 5 and supporting a brush shaft 7 at the outer ends. A rotary sweeping brush 8 is secured to shaft 7 which is caused 40 to revolve by means of pinions 9 which mesh with gears 5. Brush raising and lowering mechanism may be provided in a form of rod 10, bell crank 11 and hand rod 12. Conveyer hangers 13 are revolvably mounted upon 45 shaft 3 and support a conveyer shaft 14 and stub shaft 15. Pinions 16 and 17 are mounted upon stub shafts 15, the former engaging the gears 5 and the latter engaging conveyer pinion 18, which are secured to the conveyer 50 shafts 14. An endless conveyer 19 passes around a roller 20 which is secured to the conveyer shaft 14. The conveyer also passes around a head roller 21 which is mounted upon the body 1. A brush apron 22 is pivotally secured to hangers 13 and normally

bridges the space between the brush 8 and the conveyer 19. Conveyer raising means in the form of a rod 23, bell crank 24 and hand rod 25 may be used to raise the hangers 13 and thereby release the tension on the 60 endless conveyer. It will be apparent from the description that our device is operated entirely from the traction wheels 4 and that the brush may be raised and lowered into contact with the surface of the road at the 65 will of the operator. Also the conveyer hangers may be raised and lowered to suit the tension of the conveyer belt. In operation the brush 8 sweeps the dirt rapidly up and over the apron 22 and on to the endless 70 conveyer belt 19, which in turn carries the dirt up and over the head roller 21 and deposits it in the box 1. There is some available space in the box 1 behind the conveyer which may be utilized for carrying rub- 75 bish, etc.

While we have shown a particular form of embodiment of our invention, we are aware that many minor changes therein will readily suggest themselves to others skilled 80 in the art without departing from the spirit and scope of the invention, and we therefore desire to avoid being limited to the exact form shown and described.

Having described our invention, what we 85 claim as new and desire to protect by Letters Patent, is—

In a rotary street sweeper having a wagon body mounted upon front and rear axles, the combination of hangers mounted on the 90 rear axle and extending rearwardly and downwardly therefrom, a rotary sweeper supported in the hangers, means for raising and lowering the sweeper, conveyer supporting hangers mounted on the rear axle 95 and extending forwardly and downwardly therefrom in front of the sweeper, a roller mounted between the conveyer supporting hangers, a roller mounted in the wagon body, a continuous conveyer passing around the two rollers and extending through the wagon body, a gear wheel on the rear axle, gearing on the conveyer hangers meshing with the gear on the rear axle, and means 100 connected to the conveyer supporting hangers to raise and lower the lower end of the conveyer. 105
